UNITED STATES PATENT OFFICE.

ERASTUS E. WINKLEY, OF LYNN, MASSACHUSETTS.

MACHINE FOR OPERATING UPON SOLES.

1,196,727.

Specification of Letters Patent. Patented Aug. 29, 1916.

Application filed November 20, 1914. Serial No. 873,129.

To all whom it may concern:

Be it known that I, ERASTUS E. WINKLEY, a citizen of the United States, residing at Lynn, in the county of Essex and State of Massachusetts, have invented certain new and useful Improvements in Machines for Operating Upon Soles; and I do hereby declare the following to be a full, clear, and exact description of the invention, such as will enable others skilled in the art to which it appertains to make and use the same.

The present invention relates to a machine for operating upon shoe soles and more particularly to a machine of this character for operating upon a sole before it is incorporated in a boot or shoe.

It is customary in manufacturing certain classes of shoes to trim the flat sole to substantially the desired shape before it is incorporated in the shoe, and in connection with this rounding operation, as it is termed, it is desirable to bevel the marginal portions of the shank.

One object of the present invention is to provide a machine of this type which performs the operations of rounding the sole and skiving the shank of the sole in an improved manner and with a minimum amount of attention upon the part of the operator.

With this object in view a feature of the invention consists in the combination of sole rounding mechanism, mechanism for skiving the shank of the sole, and means for operating the rounding and skiving mechanisms automatically and in the sequence named.

A further feature contemplates in a machine of this type, mechanism for clamping a flat sole in operative position, sole rounding mechanism, and means under the control of the operator for actuating the sole clamping mechanism and permitting the operation of the sole rounding mechanism.

A further feature of the invention consists in the combination of sole clamping mechanism, sole rounding mechanism, means for actuating the sole rounding mechanism, and means under the control of the operator for actuating the sole clamping mechanism automatically locked in operative position until the completion of a cycle of operations by the sole rounding mechanism.

Certain of the above features are equally applicable to machines in which either the sole rounding or skiving operations are per-

formed singly, and these features are not to be considered as limited to their employment in a machine of this character, but are to be considered broadly in connection with machines of this general type.

Still further features of the invention consist in certain novel features of construction, combinations and arrangements of parts hereinafter described and claimed, the advantages of which will be obvious to those skilled in the art from the accompanying description.

In the drawings illustrating the preferred form of the invention; Figure 1 represents a side elevation of the improved machine; Fig. 2 a top plan view of the machine shown in Fig. 1 with the clamping head removed and illustrating the skiving knives in an inoperative position to permit the operation of the rounding mechanism; Fig. 3 is a view similar to Fig. 2 illustrating the skiving knives in an operative position prior to the skiving movement; Fig. 4 is a left hand end elevation of the machine shown in Fig. 1; Fig. 5 is a detail illustrating the mechanism for controlling the operation of the skiving knives; Fig. 6 is a detail illustrating another view of the mechanism shown in Fig. 5; Fig. 7 is a right hand end elevation of the machine with the skiving mechanism and clamping head removed; Fig. 8 is a detail partly in section illustrating the mechanism for locking the operating treadle in a depressed position during the operation of the machine. Fig. 9 is a detail illustrating a plan view of one of the rotary knife carrying arms and showing the position of the knife in operative relation to the sole; Fig. 10 is a side elevation of the arm shown in Fig. 9; Fig. 11 is an end elevation of the arm shown in Fig. 9 and illustrating the manner in which the knife operates upon a sole; and Fig. 12 is a detail illustrating the rotary knife carrying head.

The illustrated embodiment of the invention shows a rounding machine of the general type disclosed in the patents to Mayo, No. 882,009, March 17, 1908, and No. 1,091,071, March 24, 1914. This machine comprises a standard 1 carrying an overhanging arm 2 upon the outer end of which is supported a clamping head indicated at 4. This clamping head is actuated in the usual manner through a lever 5 fulcrumed upon the arm at 6 and connected with an

actuating treadle 7 through a connecting rod 8. The sole blank is supported upon a stationary pattern 10 connected to the standard 1 through a column 12. The sole 5 is trimmed by a movable rounding knife which is caused to travel completely around the edge of the sole and is guided by engagement with the pattern 10. The rounding knife 14 is supported upon the inner end of an arm 16 located upon the knife carrier 17. The knife carrier is slidably mounted on a rotary table 18 journaled upon the column and operated in the usual manner from the driving shaft through the intermeshing bevelled gears 19 and 20. The operation of the rounding mechanism is controlled by a shipper handle 22 which permits the connection of the drive pulley 23 with the drive shaft to cause the rotation of the table 18. 10 After the table has made one complete rotation the driving mechanism is automatically disconnected and the brake indicated at 25 is applied through the engagement of a tripping lever 26 with a trip 27 carried by the rotary table. It is desirable in connection with this type of machine to prevent the operation of the rounding or other mechanism until the sole has been firmly clamped in position. To this end mechanism is provided for normally preventing the operation of the actuating mechanism and this locking mechanism is connected with the clamping head in such a manner that the operation of the rounding mechanism is permitted when the clamping head is moved into an operative position. A bell crank is fulcrumed at 30 upon the machine frame and is provided with an arm 31 connected to the treadle 7 by a link 32. The second arm 33 of the bell 20 crank is connected to a latch rod 35 having a tooth 36 engaging with a coöperating tooth 37 formed upon a slide rod 38. The end of the rod 38 is normally positioned in front of one arm 40 of a bell crank fulcrumed at 30 and having its second arm 42 connected with the shipper handle through a link 43 and an arm 44 formed integrally with the shipper handle. This construction normally prevents a movement of the shipper handle to start the sole rounding mechanism, but upon a depression of the treadle the slide rod 38 is moved out of the path of the arm 40 through the above described connections, permitting the depression of the shipper handle and consequent actuation of the machine. Upon the depression of the shipper handle to start the rounding mechanism the coöperating teeth 36 and 37 are disengaged by a depending arm 46 which 30 engages with the outer end of the latch rod 35 and depresses it against the action of a spring 47. This permits the return of the slide rod 38 to its initial position under the action of the spring 45, as will be obvious to those skilled in the art.

The shank skiving mechanism is supported upon an arm 50 projecting from the standard 1 and the skiving knives are mounted upon a knife carrying head 52 which is slidably supported upon parallel 70 guide rods 53 and 54 secured upon the arm 50. Two skiving knives are employed, each operating simultaneously upon opposite margins of the sole and each knife indicated at 55 is supported upon the outer end of a 75 knife carrying arm 56 fulcrumed upon the head 52 and controlled during the lengthwise movements of the head to cause the knives to operate properly upon the sole. During the outward movement of the head 80 the knives are retained out of engagement with the sole by arms 57 extending rearwardly from the knife carrying arms and contacting with stationary cam surfaces indicated at 59. As the knife carrying head 85 is moved forward to bring the knives into an operative position the free ends of the arms 57 ride first along the cam plates 60, then on to the pivoted cam levers 61, which are normally retained in the position shown 90 clearly in Fig. 3, and finally on to the stationary cam plates 62. On the return movement of the head the arms 57 are permitted to pass behind the cam levers 61, as shown clearly in Fig. 3, and allow the skiving 95 knives to follow the contour of the pattern and skive out the margins of the sole. The knives are normally moved together into an operative position by tension springs 63 which connect the free ends of arms 64 projecting rearwardly from the knife carrying arms 56 with the head 52. The mechanism for controlling and guiding the movements of the knife carrying arms is substantially similar to that shown and described in the 100 co-pending application of Winkley, No. 606,104, filed November 2, 1914, and in consequence, has been only briefly described herein. 105 It is customary in rounding machines of this type to automatically stop the mechanism with the rounding knife positioned at the toe in order to permit the convenient removal of the sole and at the same time cause the knife to act as a gage for the 110 positioning of a new sole blank in the machine. In the present invention the skiving mechanism acts conjointly with the rounding mechanism and upon the approach of the rounding knife toward the toe upon the 115 completion of its movement around the sole the skiving knives are automatically moved forward into an operative position. When the rounding knife has completed its operation the skiving knives are ready to commence the rearward or skiving movement, thus causing the two operations to be performed without interference and in a minimum of time. The skiving mechanism is 120 operated by a counter-shaft 65 operated 125 130

from the drive pulley 23 through pulleys 66 and 67, and a connecting belt. The counter-shaft 65 operates a cam shaft 70 through intermeshing worm gears 71 and 72. The proper traversing movements are imparted directly to the knife carrying head by an actuating lever 73 fulcrumed upon the arm 50 at 74 and having its upper end pivoted to the knife carrying head. The actuating lever is operatively connected with a rotary path cam 75 through an arm 76 connected to the lever and having its free end engaging with the cam. 5

The movements of the actuating cam are automatically controlled to start the cam at the proper time to cause it to make one complete rotation and stop the cam at the completion of the skiving operation. To this end the driving pulley 67 is connected 10 to the counter-shaft 65 through a Horton clutch indicated at 80. The clutch is controlled automatically by a rocker arm 81 supported upon one end of the rock shaft 82, as shown clearly in Fig. 3, and operating 15 in the usual manner to connect or disconnect the clutch through the engagement of a tooth 83 with a lug 84 formed upon a part of the clutch. The opposite end of the rock shaft 82 carries a flat arm 85 which is actuated at predetermined intervals to lift the arm 81 and permit the operation of the clutch in the direction of the arrow in Fig. 4. The movements of the arm 85 are imparted by a lever 87 fulcrumed loosely upon 20 one end of the shaft 82 and having one end engaging with the face of a rotary cam 90 secured to the under side of the rotary table 18. The initial movement of the cam member 90 permits the inner end of the lever 25 87 to be swung upwardly by a tension spring 91, allowing a pin 92 slidingly supported upon the arm 85 to be moved beneath a projection 93 formed upon the lever 87. The pin 92 is normally projected into 30 the position shown in Fig. 5 by a spring 95. It will be observed from an inspection of Figs. 2 and 4 that after approximately one half a revolution of the table 18 the lever 87 is again depressed by the cam 90 carrying 35 the arm 85 with it through the pin 92 and projection 93 and at the same time raising the arm 81 to cause the connection of the clutch members. This operation takes place when the rounding knife is completing its 40 traverse about the sole edge and is moving toward the toe of the sole, thus causing the skiving knives to advance and follow the rounding knife as it moves toward the toe. When the rounding knife reaches the toe 45 the skiving knives are then ready to commence the operative movement to skive out the opposite margins of the shank and when this movement is completed and the knives have returned to the position shown in Fig. 50 2 the skiving knife actuating mechanism is

automatically disconnected. To this end the pin 92 is provided with a disconnecting lever 96 fulcrumed upon the arm 85 at 97 and having its free end located in the path of a lug 98 projecting from the face of the 70 worm gear 71. When the disconnecting lever is oscillated to remove the pin 92 from beneath the projection 93 a spring 100 serves to oscillate the rock shaft and return the arm 81 to the position shown in Fig. 4, 75 in which position the tooth 83 engages with the lug 84 and disconnects the Horton clutch at the completion of a cycle of operations.

It is desirable after the sole has been clamped in position by the operator to provide means for locking the clamping mechanism in operative position until the machine has stopped and to furthermore provide means for automatically releasing the clamping head upon the completion of a 80 cycle of operations. To this end the treadle 7 is normally locked in a depressed or operative position by a sliding stud 101 pivot to the treadle and passing through a box 102 which is provided with a recess containing a roll 103 bearing against the face of the stud 101 and normally pressed up by a spring 104 to grip the stud in the usual manner and prevent an upward movement. The clutch is released automatically to permit the elevation of the treadle under the action of the spring 104 connected to the clamping head. This is accomplished by the engagement of a lug 105 formed upon the periphery of the path cam 75 with an arm 106 fulcrumed upon the frame at 107, as shown clearly in Fig. 1 and connected with a lever 108 through a link 109. The lever 108 is normally moved in a direction to maintain the arm 106 in engagement with the peripheral surface of the path cam by a tension spring 110 and the free end of the lever is connected through a link 111 to an oscillatory dog 112 which actuates a releasing block 113 to depress the locking roll 103 90 against the action of the spring and release the clutch. 95

In order to improve the cutting action it is desirable to provide rotary cutting knives which are positively operated at a suitable 100 rate of speed. To this end each skiving knife indicated at 55 consists of a rotary head 115 to which are secured a series of cutting blades 116 by suitable threaded fastenings 117. The cutting blades are provided with beveled cutting faces to skive the sole as shown in Fig. 11 and the rotary knife head is mounted upon the lower end of a shaft 119 journaled in the outer end of the knife carrying arm 56. The upper end 115 of the knife shaft 119 is provided with a gear 120 which meshes with a large driving gear 121 journaled upon the knife carrying arm. The driving gear 121 is operated 120 through a driving sprocket 122, chain 123 125 130

and driving sprocket 124 journaled at the fulcrum of the knife carrying arm 56. Each of the driving sprockets 124 is operated by a spiral gear 126 mounted upon a 5 drive shaft 127 journaled in the head 52. The shaft 127 is provided with a drive pulley 128 which is operated in any suitable manner to constantly rotate the skiving knives during the back and forth traverse 10 of the knife carrying head. As shown clearly in Figs. 1 and 3, each driving chain is inclosed by a casing 130, the intermeshing gears by a casing 131, and the rotary skiving knife by a guard or casing 133. The 15 knife guard, as shown clearly in Figs. 9 and 10 comprises a curved shield fulcrumed upon the knife carrying arm at 135 and having its free end caused to follow the contour of the sole by a coil spring 136. The inward 20 movement of the curved shield 133 is limited by the contact of a stop screw 138 with the face of the knife carrying arm, as shown in Fig. 9. The rotary knife is retained in engagement with the surface of the sole during 25 the cutting operation and is guided to follow the contour of the pattern by a combined guide member and presser foot indicated at 140 which has a guiding face arranged to engage with the side of the pattern, 30 as shown clearly in Fig. 11, and a portion 141 which is arranged to project beneath the pattern and retain the knife in engagement with the surface of the sole. The knife may be adjusted relative to the 35 presser foot 141 to vary the depth of cut through the provision of a separable dovetailed connection indicated at 142. The knife is firmly clamped in any adjusted position by a set screw 143.

40 While it is preferred to employ the specific construction and arrangement of parts shown and described, it will be understood that this construction and arrangement is not essential except so far as specified in the 45 claims, and may be changed or modified without departing from the broader features of the invention.

The invention having been described, what is claimed is:

50 1. A machine for operating upon shoe soles, having in combination, sole rounding mechanism, shank skiving mechanism, and connected mechanism acting in timed relation for operating the sole rounding and 55 shank skiving mechanisms automatically to first round the sole and to next skive out the marginal portions of the shank of the sole.

60 2. A machine for operating on soles, having in combination a pattern, a trimming knife co-operating with the pattern to round the sole, mechanism for causing the trimming knife to traverse about the pattern, mechanism for stopping the trimming knife at the completion of the traversing movement, shank skiving mechanism, and means

for operating the skiving mechanism after the trimming knife has completed its movement.

3. A machine for operating upon soles, having in combination, a pattern, a trimming 70 knife co-operating with the pattern, mechanism for causing the trimming knife to traverse about the pattern and stop opposite the toe, shank skiving mechanism, and means for actuating the skiving mechanism when the trimming knife is in an inoperative position at the toe. 75

4. A machine for operating upon soles, having in combination, a trimming knife, mechanism for actuating the trimming 80 knife, shank skiving mechanism, a cam for operating the skiving mechanism, and control mechanism for starting the cam and skiving mechanism when the trimming knife is completing the rounding operation. 85

5. A machine for operating upon soles, having in combination, sole rounding mechanism, shank skiving mechanism, a common actuating means for the sole rounding and shank skiving mechanism, and means for 90 successively connecting the sole rounding and shank skiving mechanisms to the actuating mechanism.

6. A machine for operating upon soles, having in combination, a trimming knife, a 95 pattern, mechanism for causing the trimming knife to traverse completely about the pattern, shank skiving knives, mechanism for actuating the knives lengthwise of the pattern, and control means for causing the 100 skiving knives to be moved into an operative position during the continued movement of the trimming knife about the pattern.

7. A machine for operating upon soles, having in combination, a pattern, a clamping head, a trimming knife, actuating mechanism for the trimming knife, a shipper handle for starting the actuating mechanism, a treadle for operating the clamping head, a bell crank connected to the treadle, 105 and connections between the bell crank and shipper handle for preventing the operation of the shipper handle until the treadle is depressed to actuate the clamping head. 110

8. A machine for operating upon soles, 115 having in combination, a pattern, a clamping head, a treadle for operating the clamping head, a sole rounding mechanism, a shank skiving mechanism, means for operating the mechanisms successively, and means for locking the clamping head in an operative position and for releasing the head 120 automatically at the completion of the shank skiving operation.

9. A machine for operating upon soles, 125 having in combination, sole rounding mechanism, shank skiving mechanism, a cam for operating the shank skiving mechanism, a clamping head, a treadle connected to the clamping head, means for locking the treadle 130

in a depressed position, and control means operated by the cam for releasing the treadle at a predetermined time.

10. A machine for operating upon soles, having in combination, sole rounding mechanism, means for actuating the sole rounding mechanism, a shank skiving knife arranged to move lengthwise of the sole, a rotary cam, connections between the cam and actuating mechanism, and connections between the cam and skiving knife for moving the knife lengthwise of the sole.

11. A machine for operating upon soles, having in combination, a trimming knife, mechanism for actuating the trimming knife, a skiving knife, mechanism for actuating the skiving knife including a clutch, and means for automatically connecting the clutch to operate the skiving knife at a predetermined point in the movement of the trimming knife.

12. A machine for operating upon soles, comprising a sole pattern, an arm, a rotary skiving knife supported upon the free end 25 of the arm, a guide supported upon the arm beneath the knife and arranged to contact with the pattern to guide the knife, means for rotating the skiving knife, and mechanism for moving the arm lengthwise of the sole and for permitting the arm to oscillate 30 and follow the contour of the sole.

13. A machine for operating upon soles, comprising a sole pattern, an arm, a rotary skiving knife carried by the arm, a guide carried by the arm beneath the knife for engaging with the pattern, a presser foot carried by the arm for engaging with the under side of the pattern, and mechanism for moving the knife lengthwise of the pattern and for permitting lateral movements of the 35 knife with relation to the pattern.

14. A machine for operating upon soles, comprising a pattern, an arm, a rotary skiving knife supported upon the end of the arm, and a guard supported upon the 40 arm surrounding the knife and arranged to yieldingly engage with the pattern in advance of the knife.

15. A machine for operating upon soles, comprising a stationary pattern, a clamping 45 head, a rotary table, a trimming knife carried by the table, shank skiving mechanism, a cam carried by the rotary table, and connections between the cam and shank skiving mechanism for operating the mechanism at 50 a predetermined point in the movement of the table.
